UNITED STATES PATENT OFFICE.

CLAY HENRY JACOBS, OF DELTA, IOWA.

ADJUSTABLE SIGN

Application filed October 4, 1923. Serial No. 666,535.

To all whom it may concern:

Be it known that I, CLAY H. JACOBS, a citizen of the United States, residing at Delta, in the county of Keokuk and State of Iowa, have invented certain new and useful Improvements in Adjustable Signs, of which the following is a specification.

The present invention relates to signs and particularly of that type adapted to be placed on display in store windows or against panes of glass and the like.

An object of the invention is to provide a sign with an open uninterrupted frame through which light rays may freely pass without casting any shadows tending to detract from the lettering or other configurations placed in the frame, and a frame which will removably support panels bearing lettering or other configurations which it is desired to display in the frame.

A further object of the invention is to provide an adjustable frame which is capable of being adjusted to narrow and wide windows or adjusted vertically when placed on end to accommodate windows of various heights, the frame having a number of sections each with an independent securing device for not only holding the sign in place but for also maintaining the parts or sections in adjusted position.

A still further object of the invention is to provide a sign embodying the above characteristics and which at the same time may be attached to the surface of a pane of glass or the like without the use of nails or screws and by the use of suction cups in desired numbers for not only supporting the weight of the sign but also holding the sections in their relative positions.

The invention also aims at the provision of an extensible frame comprising a pair of sections having top and bottom rails which are rolled or bent to provide interfitting and telescoping channel portions which interbrace each other and not only provide a rigid frame but also provide the necessary grooves or channels for the reception of the top and the bottom edges of the panels which are interchangeably fitted in the frame.

The above and various other objects and advantages of this invention will in part be described in and in part understood in and from the following detailed description of the present preferred embodiment, the

same being illustrated in the accompanying drawing, wherein:

Fig. 1 is a front elevation of a sign constructed according to the present invention and being collapsed into small size. 60

Fig. 2 is a similar view of the sign extended for covering a larger area.

Fig. 3 is a rear elevation of the frame of the sign with the parts or sections thereof separated. 65

Fig. 4 is a view similar to Fig. 1 but showing opaque instead of transparent panels in the frame.

Fig. 5 is a transverse section taken through the sign substantially on the line 5—5 of Fig. 1, and being an enlargement thereof.

Fig. 6 is an enlarged fragmentary section taken through the end of the sign on the line 6—6 of Fig. 2, and

Fig. 7 is a fragmentary sectional view, enlarged, through an intermediate portion of the sign, showing the telescoping rails of the frame and fitting of a panel in the channel of the frame. 75

Referring to the drawing 10 and 11 designate a pair of frames the top and bottom or side rails of which are arranged to telescope one within the other so that the frame sections may be extended and collapsed to provide a sign of the desired width or height. 85

As shown particularly in Fig. 7 the outer frame 10 has a substantially closed channel shape portion terminating at the rear side of the frame in a downwardly opening channel or groove 12 which is formed by the overturning of the end of the rail of the frame. The frame section 11 is similarly formed but on a sufficiently reduced scale to slidably and snugly fit within the rail of the section 10 and terminates at the rear side of the section 11 in a channel or groove member 13 adapted to engage about the channel or groove member 12 for reinforcing and stiffening the same. 95

The construction shown in Fig. 7 prevails at the bottom or opposite side of the frame so that the channel or groove in the member 12 and in the member 13 is continuously entirely about the frame and opens towards the middle thereof. 100

The frame is adapted to carry one or more panels 14 which are preferably transparent but which may be opaque as shown at 15 in Fig. 4. These panels carry configurations 16 thereon which may be in the 110

- form of letters as shown, or of any other desired configuration suitable for use in a sign. The transparent panels 14 are adapted to permit the passage of light rays through the sign, and the telescoping rails of the frame are in the form of substantially closed channels to eliminate the necessity of cross braces, webs or other devices which would cast or throw shadows upon the panels 14 and would consequently change the visual aspect of the configurations 16. The frame is therefore open and free at its middle and at the same time is rigid and capable of adjustment.
- 15 Each of the sections 10 and 11 is provided with one or more suction cups 17 adapted to be placed against the inner side of a pane of glass for holding the sign in position by suction. By use of the suction cups the sign 20 is not only supported on the glass but the sections 10 and 11 are rigidly held in their relative positions to hold the panels 14 in the channels 12 and 13 of the frame. The frame may be contracted as shown in Fig. 1 25 where a small sign is needed and it may be extended to provide a long sign where it is necessary to display a long word or configuration as shown in Fig. 2.
- The panels 15 may be used where it is not necessary to utilize the light in a store or the like for setting out the configurations on the panels. In the structure shown in Fig. 4 the configurations 16 are displayed for reading by reflected light and the panels 15 may be of card board or other suitable material which admit flexing as shown at the left end of Fig. 4 to facilitate the positioning and removal of the panels 15. Of course the panels

14 may be of any suitable material provided they be transparent so that the configurations 16 may be set off by the light rays which are projected through the frame. The sign may be placed in a store window or the like and secured against the inner side of a pane of glass so that the light in the store may be projected through the pane and through the sign, illuminating the panels while the configurations 16 arrest the light rays and throw the necessary shadows for reading the sign.

It is of course understood that various objects other than the above may be accomplished with the use of this sign, and that various changes and modifications within the scope of the following claim may be made over the above specifically described embodiment without departing from the spirit of this invention.

What is claimed is:

A sign comprising a frame having a pair 60 of sections with hollow side rails of different dimensions and adapted to interfit for sliding one section upon the other, said rails having channel portions opening toward the middle of the frame and being slidable one 65 upon the other for extending about the inner side of the frame, and a plurality of transparent panels fitting in said channels of the frame and bearing opaque indicia adapted to arrest the projection of light rays through 70 the frame, and a suction cup on each section of the frame adapted to be secured against a pane of glass for holding the sign and for maintaining the sections in adjusted position.

CLAY HENRY JACOBS.
